UNITED STATES PATENT OFFICE.

LOUIS KOSSUTH JOHNSON, OF BROOKLYN, NEW YORK.

TYPE HOLDER AND SEPARATOR.

SPECIFICATION forming part of Letters Patent No. 277,740, dated May 15, 1883.

Application filed February 4, 1882. (No model.)

To all whom it may concern:

Be it known that I, LOUIS K. JOHNSON, a citizen of the United States, residing at Brooklyn, in the county of Kings and State of New York, have invented a new and useful Type Holder and Separator, of which the following is a specification.

This invention relates to devices for holding a page or column of type that has been used and presenting the same to the operator for redistribution by hand. Heretofore, so far as I am aware, these devices have consisted of a simple galley or box inclined at a suitable angle and furnishing support for a column of type placed therein in such manner that the types could only be removed from the top of said column. The mode of grasping and removing the types was thus rendered inconvenient and difficult, since, as the face of the uppermost line of type occupied the same plane as that of the rest of the column, the types required had to be drawn forward by pressure applied above by one or more fingers before they could be grasped between the fingers and thumb. This operation was retarded and rendered still more difficult from the fact that all type that has been used is more or less "gummed" or stuck together, even after being subjected to the ordinary process of washing, thus necessitating the application of considerable force in order to separate a portion of the upper line from the rest and from the line underneath. For the same reason the portion of the line removed had always to be "broken" or separated by and between the thumb and fingers before the individual types could be dropped into their respective compartments or receivers.

It is the object of my invention to avoid these objections and to facilitate hand distribution by presenting each line of type as required in a convenient position to be grasped at once between the thumb and fingers, and with the line thoroughly broken or loosened, so that its component parts may be readily disposed of.

My invention consists, first, in a galley or type-holding compartment formed at the bottom with a type-column-supporting shoulder or floor of sufficient width to project in front of the position of the column of type the requisite distance to support a line of type inde-

pendently, and having its rear and side walls slotted or otherwise formed immediately above said shoulder or floor to receive and allow the advance and retraction of a separator or "breaker" pivoted at one extremity in such relation to the type-holder that in its forward movement it will impinge against the individual types composing the lowest line of the column, separately and consecutively, so that they will be detached or loosened from each other by the time the line has been pushed forward into position to be grasped by hand; secondly, in making the separator-blade, so pivoted, and the transverse receiving-slot in the lower side walls of the holder of less width than the width of the narrowest type to be used, so that the lowest line in a column will always be held against any tendency to lateral displacement, thereby aiding and insuring the action of the separator-blade in "breaking" the line during the operation of cutting it off from its column; thirdly, in an adjustable side wall or partition for sustaining columns of type of variable width in the holder against lateral displacement ending above the type-supporting shoulder or floor a distance equal to the thickness of the type-blade of the separator and less than the width of the smallest type to be used, so as to allow the separator to pass freely underneath, while at the same time it may be made to bear against that side of the lowest line of type.

In the accompanying drawings, Figure 1 is a front elevation of my improved device; Fig. 2, a side elevation; Fig. 3, a plan; Fig. 4, a side elevation, showing the galley secured in a horizontal position; Fig. 5, a projection on the plane of the type-supporting shoulder A', partly in section; Fig. 6, a section through the type-supporting floor or shoulder and the lower side walls of the galley on line y y, Fig. 5.

The type holder or galley A is pivoted upon a bracket or support, a, in such manner that it may be turned back and secured in a horizontal position, as indicated in Fig. 4, for greater convenience in filling and adjusting. When arranged for use it is preferably made to assume an inclined position, as shown in Fig. 2, at least sufficient to cause the type to rest steadily in the holder by its own gravity. The holder is sustained in this position by inclined rests or stops a' a', projecting from the

supporting bracket *a*, or by other suitable means.

The column of type *T* is supported within the holder *A* upon the floor or supporting-
5 shoulder *A'*. This latter projects forward be-
yond the front edges of the holder *A* a suffi-
cient distance to furnish a support or rest for
a line of type beyond and in front of the base
of the column of type contained in the holder.

10 This projection *b* (which forms the lower lip of
the line-holder *B*) is equal, say, to about five-
eighths or seven-tenths of "type-high," so as to
leave the front of the line of type *t*, when in
position, exposed sufficiently to be readily
15 grasped between the thumb and fingers.

In order to sever the lowest line of the
column of type and bring it into its independent
position between the lips of the line-holder *B*,
20 I pivot one end of a separator and line-breaker,
C, (which is simply a straight-edge or blade)
to the floor or supporting-shoulder *A'* in such
manner that when it is at the end of its for-
ward stroke its front edge will coincide with
25 the face of the column of type contained in
the holder, as indicated in Figs. 1, 2, 3, and 5.

As the separator *C* recedes during its back
stroke the column of type descends by its own
gravity, so as to bring its lowest line against
the floor or supporting-shoulder *A'* into pos-
30 tion to be in turn pushed forward into the line-
holder *B* by the next forward stroke of the
separator.

In order to detach the types in the line one
35 from the other, or, technically, to "break" the
line, I pivot the breaker or separator *C* to the
floor or supporting-shoulder *A'* at a point be-
yond and in advance of the position occupied
40 by the rear of the column of type in the holder
A, as indicated in Figs. 2 and 5, so that in its
forward movement the front edge of the sepa-
rator will first encounter and start forward
45 the first type on the extremity of the lowest
line in the column next the pivot, and then the
next type in said lowest line, and so on in suc-
cession until all the types in the said line have
50 been started and pushed forward into the line-
holder *B*, where they are again brought into
line with relation to each other by the com-
pletion of the forward stroke of the separator
55 *C*, as before indicated. By thus bringing the
edge of the breaker *C* into contact with each
type independently and successively I am en-
abled to overcome any adhesive tendency be-
tween the types arising from "gumming" or
60 imperfect cleaning, and I accomplish this with-
out any additional labor or loss of time by and
during the simple act of separating the line from
the column. In order to facilitate this result and
render the independent movement or start of
65 each type certain, I confine the extremities of the
lowest line between the vertical shoulders *c c'*,
as illustrated in Fig. 6, so that all tendency to
lateral displacement is counteracted and the
types are compelled to preserve their align-
70 ment in moving forward. It is thus obvious
that each type must necessarily be started for-
ward by the pusher *C* before the latter can

come in contact with the next succeeding type.
I accomplish this lateral support for the lowest
line by making the pusher *C* and the corre-
70 sponding transverse slots in the walls of the
holder of less width than that of the smallest
type to be used, as indicated in Figs. 2 and 6.
By making the slot in the rear wall of the
75 holder *A* of also the same width I support the
said last line against displacement in that di-
rection.

The breaker and separator *C* may be formed
with a handle, as shown, and operated by
hand; or it may be provided with a retractile
80 spring and operated by a treadle, if desired.

The line-holder *B* consists of the projection
b, of the supporting-floor *A'*, forming the lower
lip, and of the upper lip or flange, *b'*, which
holds the line against vertical displacement.
85 A guiding and retaining plate, *G*, is secured
to the front of the holder immediately above
the line-holder *B*, and projects upward a suffi-
cient distance to retain the lower portion of
90 the column and guide it accurately to position
upon the supporting-shoulder *A'*.

In order to compensate for variations in the
width of the pages or columns of type to be
distributed, I provide a movable side wall or
partition, *D*, which may be adjusted to just
95 touch the side of the column of type and sus-
tain the latter in position without binding it or
retarding its descent. The distance between
the lower extremity of this movable side wall
and the upper surface of the type-supporting
100 floor *A'* is just sufficient to allow the passage
of the separator *C* underneath, and is less than
the width of the smallest type to be used, for
the reasons before stated.

For the purpose of insuring the even de-
105 scent of the upper portion of the column, I pro-
pose to employ a follower, *F*, of sufficient
weight to carry the last line unbroken into po-
sition upon the supporting-floor.

What I claim is—

1. In combination with a type-column holder
formed with a type-supporting shoulder, sub-
stantially in the manner and for the purpose
described, a combined line-separator and line-
breaker, pivoted to the device at a point be-
115 yond and in advance of the position occupied
by the rear of the column of type in the holder
in such manner that its front edge will im-
pinge against and start forward each type in
the lowest line of type in the column inde-
120 pendently and successively during its forward
stroke, substantially in the manner and for the
purpose described.

2. A type-column holder formed with a type-
supporting shoulder, substantially in the man-
ner and for the purpose described, having
transverse slots formed in its side walls of a
width only sufficient to admit a pivoted line-
separator of a thickness less than the width of
the narrowest type to be used, in combination
125 with such pivoted line-separator, substantially
in the manner and for the purpose described.
130

3. In combination with a type-column-sup-
porting case and pivoted line separator and

breaker substantially such as designated, a movable side wall or partition for the purpose of adjusting the holder to variations in the widths of the columns of types, the lower extremity of said adjustable side wall ending a distance above the type-supporting floor or shoulder less than the width of the narrowest type to be used, substantially in the manner and for the purpose described.

LOUIS KOSSUTH JOHNSON.
